Carpets

(Apr. 1-1871.)

No. 11,136.

UNITED STATES PATENT OFFICE.

DAVID MCNAIR, OF BOSTON, MASSACHUSETTS, ASSIGNOR TO ROXBURY
CARPET COMPANY, OF SAME PLACE.

DESIGN FOR CARPET.

Specification forming part of Design No. **11,136**, dated April 1, 1879; application filed February 26, 1879.
[Term of patent 3½ years.]

To all whom it may concern:

Be it known that I, DAVID MCNAIR, of Boston, in the county of Suffolk and State of Massachusetts, have invented a new and original Design for Carpets, of which the following is a specification:

The nature of my design is shown in the accompanying photographic illustration; and it consists in the arrangement and configuration which I will now describe, referring to said photographic illustration, in which—

a a a, &c., represent a series of figures which extend in rows along the piece, the figures in one row alternating with those in the adjoining rows, as shown. Each figure *a* is generally rectangular in shape, (excepting at its corners, which are formed with re-entrant angles,) and is provided with a central ornament resembling a spray of leaves. *e e*, &c., represent approximately elliptical figures alternating with the figures *a*, and *f g* represent bor-

der-like figures extending between the figures *a* and *e* in two directions, as shown. On the groundwork of the carpet, between the figures *a*, are floral designs arranged to give the effect of lines or rows of flowers, *b b b* and *c c c c*, extending diagonally across the piece, and broken or interrupted by the figures *a e*.

I claim—

1. The design for carpets, consisting of the figures *a* and *e* and the border-like figures *f g*, substantially as shown.
2. The design for carpets, consisting of the figures *a* and *e* and the floral designs *b c*, substantially as shown.

In testimony whereof I have signed my name to this specification in the presence of two subscribing witnesses.

DAVID MCNAIR.
